UNITED STATES PATENT OFFICE.

EDWARD F. DUDLEY, OF OAK PARK, ILLINOIS, ASSIGNOR TO MIEHLE PRINTING PRESS & MANUFACTURING COMPANY, OF CHICAGO, ILLINOIS, A CORPORATION OF ILLINOIS.

CHASE MOUNTING.

Application filed April 22, 1922. Serial No. 555,954.

To all whom it may concern:

Be it known that I, EDWARD F. DUDLEY, a citizen of the United States, residing at Oak Park, in the county of Cook and State of Illinois, have invented certain new and useful Improvements in Chase Mountings, of which the following is a specification.

This invention relates to printing presses and more particularly to a chase mounting 10 therefor.

One object of the invention is to provide simple, reliable and efficient means for raising, lowering and angling the chase frame.

Another object is to provide an improved 15 mounting for a chase frame in which all the parts are accessible and cooperate in a manner to meet the various requirements for successful commercial use.

These and other objects are accomplished 20 by means of the arrangement disclosed on the accompanying sheet of drawings, in which—

Figure 1 is a fragmentary elevational view 25 of parts of the printing press embodying my invention;

Figure 2 is a sectional view taken in the plane of line 2—2 of Figure 1; and

Figure 3 is a sectional view taken in the plane of line 3—3 of Figure 1.

The various novel features of the invention 30 will be apparent from the following description and drawings, and will be particularly pointed out in the appended claims.

Referring to the figures of the drawings, 35 it will be noted that I have disclosed my invention in connection with a printing press having way-frame members 10 in which the type bed 11 is mounted for reciprocation. Secured to the type bed 10 is an inking plate 12, which lies below the chase frame 13 in which the plate or type, 40 not shown, is mounted.

This invention has to do primarily with the chase mounting. When a chase is set 45 in cooperative position with the type bed it may be found to be too low or too high, or it may be found to be slightly out of vertical alignment. Accordingly, it is desirable to provide some simple and reliable

means for adjusting the position of the chase. To this end I have provided means 50 which, in this embodiment of the invention, includes two jack studs 14 which are threaded into suitable threaded portions 15 of pockets 9 in the upper portion of the ink-

ing plate 12 near the opposite sides thereof. It is the lower end 16 of each stud 14 which is threaded and directly thereabove is a large cylindrical guide portion 17 which fits snugly and cooperates with a barrel 60 portion 18 of the pocket 9. Above this barrel portion the stud is provided with a head 19, the upper portion of which is cone-shaped and has its inclined sides, in this particular instance, extending at an angle 65 of 45 degrees. The lower cross bar 20 of the chase 13 has a beveled face 21 which, in this particular instance, extends at an angle of 30 degrees from the vertical. The chase is mounted and rests upon the cone-shaped heads 19 of the oppositely arranged studs 14, and the inclined surfaces of the cone-shaped heads and of the beveled face 21 of the chase are made to extend at an angle with respect to each other to facilitate 70 placing the chase in position and removing same therefrom. After the chase is placed on top of the studs or jacks 14, a clamp 22 is placed in locking position over the upper cross member 23 of the chase for locking the 75 chase in position. The locking member 22 is pivotally mounted on a stud 24 secured to the type bed 11 and is yieldably held in locking position by a coiled spring 25 surrounding a rod 26, one end of which is pivotally connected to the locking member 22 and the other end of which is guidedly received in an opening 27 in the bed 11. It is seen, therefore, that the locking member 22, when in chase locking position, will permit 80 an adjustment of the chase. If the chase is too high the jack screws or studs 14 may be lowered, whereupon the chase will follow as a result of its own weight and as a result of the tension in the spring 25. If 85 the chase is too low it may be raised by raising the jack studs 14. If one side is too high or too low that side may be lowered or raised by adjusting the associated jack stud 14. For rotating or adjusting the 90 jack studs 14 any suitable pin may be used which may be inserted in the tool or wrench openings 28.

By means of this arrangement the chase may be raised, lowered or angled even while locked to the bed in a simple manner and, at the same time, the chase may be quickly and easily applied to and withdrawn from the type bed.

It is my intention to cover all modifica-

tions of the invention falling within the spirit and scope of the following claims.

I claim:

1. In a printing press, the combination of a support, a chase, a jack stud adjustably mounted in said support and on which said chase is mounted whereby the latter may be adjusted, and means for yieldably locking said chase whereby the latter may be 10 adjusted while it is locked.
2. In a printing press, the combination of a support, a chase having its lower portion beveled, a member associated with said chase and adjustable with respect to said 15 support and having a portion inclined at a different angle with respect to said bevel for facilitating the application and withdrawal of said chase.
3. In a printing press, the combination of a support, a chase, and a stud adjustable in said support and on which said chase is mounted whereby the latter may have its position adjusted, said chase and stud having engaging portions inclined at a different 20 angle for facilitating application and with- 25

drawal of said chase with respect to the press.

4. In a printing press, the combination of a support, a chase having a portion thereof beveled, and a jack stud adjustable in 30 said support and having a conical head on which said chase is mounted for adjustment, the angle of said beveled portion and said conical head differing for facilitating application and withdrawal of said chase. 35

5. In a printing press, the combination of a support, a chase having a portion thereof beveled, a jack stud adjustable in said support and having a conical head on which said chase is mounted for adjustment, the 40 angle of said beveled portion and said conical head differing for facilitating application and withdrawal of said chase, and a spring pressed locking member for yieldably 45 forcing the chase against said jack stud and capable of yielding in accordance with adjustments of said chase.

Signed at Chicago, Illinois, this 17th day of April, 1922.

EDWARD F. DUDLEY.
